COMBINED CLOCK AND CALENDAR

John Satrazemis, 1254 Emilie St., and George D. Bielinski,
443 Floral Drive, both of Green Bay, Wis. 54301

Filed Feb. 9, 1968, Ser. No. 10,514

Term of patent 14 years

(Cl. D42—7)

FIG. 1 is a perspective view of a combined clock and calendar showing our new design;

FIG. 2 is a reduced scale front elevational view;

FIG. 3 is a right side elevational view thereof;

FIG. 4 is a rear elevational view thereof;

FIG. 5 is a left side elevational view thereof; and

FIG. 6 is a top plan view thereof.

The dotted line showing is for illustrative purposes only.

We claim:

The ornamental design for a combined clock and calendar, as shown and described.
